UNITED STATES PATENT OFFICE.

OSCAR E. A. WIESSNER, OF BROOKLYN, NEW YORK.

DESIGN FOR A BEDSTEAD.

SPECIFICATION forming part of Design No. 24,326, dated May 21, 1895.

Application filed March 20, 1895. Serial No. 542,556. Term of patent 3½ years.

To all whom it may concern:

Be it known that I, OSCAR E. A. WIESSNER, a citizen of the United States, and a resident of the city of Brooklyn, county of Kings, and State of New York, have invented and produced a new and original Design for Bedsteads, of which the following is a specification, reference being had to the accompanying drawing, in which the figure is a perspective view of a bedstead embodying my design.

The leading feature of my design consists in a bedstead, the head and foot frames being of skeleton form and comprising circular or ring shaped portions supported by vertical standards having an ornamental central portion and semi-circular arched portions or strips.

Referring by letter to the drawing A designates the posts of the bedstead connected in pairs by cross-rods $a a'$. The rods a are connected at the ends with castings a^2 , of florated design attached to the posts as shown,

and the rods a' are connected at their ends to castings a^3 of scroll design, attached to the posts.

25

A' shows a standard attached at its ends to the rods $a a'$. The standard is arranged midway between the posts A and may have an ornamental central portion.

B is a circular post or ring attached at its 30 top and bottom to the standard A' .

B' is an arched or semi-circular portion or strip extended from post to post, its lower ends starting from the rod a' and its central portion being attached to the standard A' 35 outside the ring or circular part B .

What I claim is—

The design for a bedstead substantially as shown and described.

OSCAR E. A. WIESSNER.
